UNITED STATES PATENT OFFICE.

RENA K. SALOMON, OF BROOKLINE, MASSACHUSETTS.

FURNITURE.

Application filed April 22, 1924. Serial No. 708,239.

My invention involves structures variously embodied in furniture and like appliances of different forms and sizes and for many purposes. Certain features are capable of even more general application but I have selected for illustration herein an embodiment adapted to serve as a stand, table or tabouret in average size, or as a cabinet in smaller sizes, or as a bureau or chiffonier in larger sizes.

Fundamentally in such devices the problem has been with what has generally been considered as drawers. This has meant specifically sliding compartments but more generally compartments individually available for the purpose of storage or classification. Most of such compartments have been rectangular in cross section as the usual article of furniture has been by custom generally rectangular in ultimate dimension.

My invention is in part a departure in its conception as to compartments. My compartments are substantially rhombohedral receptacles arranged in groups and each having a throw or shift forward or toward the front of the drawer or hopper. While each is generally rhomboidal in cross section they combine into an article generally rectangular in cross section and vertically lined in its general contour.

Considering my invention as embodied in such a device by way of illustration I will refer to a form which I have selected as generally representative. I have shown in the accompanying drawings a stand of such characteristic type. In these figures I have applied characters of reference which I shall employ in the following specification to designate the several parts.

Fig. 1 is a front elevation.

Fig. 2 a side elevation with compartments closed.

Fig. 3 a similar view with compartments open, and

Fig. 4 an enlarged fragmentary detail.

The structure shown constitutes a stand or tabouret, although as suggested above it may be enlarged or diminished to form articles of furniture for other purposes than that shown. As illustrated the embodiment constitutes a frame consisting of a top 1. This is preferably doubled as at 1¹ and the two parts hinged together so as to overfold each other or be capable of opening out to form a larger top. This top is carried by cross pieces 2 and is sheathed at the back as at 3

to form a socket within which the upper compartment may enter. The cross pieces 2 are preferably tapered so as to give a rearward depth to cover the rear of the upper compartment when the compartments are in normal position. The top and frame is carried by legs 4 which are footed as at 5 and crossed braced to give strength as at 5¹. The drawers or hoppers 6 are each pivoted at their ends as at 7 in the legs 4. These hoppers are linked at each side of the end by strips 7¹ pivoted as at 8 to each of the hopper ends. The top may be of any design but preferably is conveniently contoured so as to fold in two like halves 1 and 1¹. The leaf 1¹ is supported in the usual manner by an arm 9 which may be turned out as a brace. When closed the device is generally rectangular when viewed in elevation. When the hoppers are open they break out of the rectangular form and become a series of separated receptacles having an inclined front and each slightly flanged forward so that articles within them are readily accessible.

The angularity of these hoppers may be varied. Their number may be decreased or multiplied. The frame of the article may be varied and the manner of suspension and linkage changed. All these variants as well as the variations in material and finish may be practiced within the purview of my invention.

What I therefore claim and desire to secure by Letters Patent is:

1. An article of furniture comprising a top frame and lateral supporting members therefor, a plurality of compartments substantially rhomboidal in cross section pivoted to said supporting frame and disposable with their front and rear walls in substantially vertical disposition, said sections being linked each to the other whereby upon tipping on their pivots each compartment is exposed, the upper edges of the side and rear portion of the upper pivotal section being normally spaced from the top, said side and rear members of the frame being shaped to enclose the space thus formed between the upper edges of the side and rear portions of the frame and the top.

2. An article of furniture, a top frame and lateral supports therefor, a hinged top on said top frame, a pivoted support within said top frame and adapted to support the top and a plurality of compartments sub-

stantially rhomboidal in cross section and pivoted to said side support and normally disposed with a lateral inclination with the sections in contact and having their front and rear walls in a substantially vertical disposition, the upper portion of the top compartment being covered by said top support-

ing frame and links connecting said sections whereby each section will be uncovered by that next above it when any section is rocked 10 on its pivot.

In testimony whereof I affix my signature.

RENA K. SALOMON.
